UNITED STATES PATENT OFFICE

LORENZO DOW PENDER, OF RALEIGH, NORTH CAROLINA, ASSIGNOR TO L. DOW PENDER, JR., OF TARBORO, NORTH CAROLINA

BRUSH KILLER

Application filed November 4, 1932. Serial No. 641,292.

This invention relates to a hand operated tool for cutting brush, weeds, bushes and the like.

An object of the invention is to assemble a handle and blade in a new and novel manner whereby the handle will not be subjected to splitting and breaking strains.

Another object is to so locate the handle on the blade as not to interfere with the sharpening of either or both edges of the blade.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawing the preferred form of the invention has been shown.

In said drawing

Figure 1 is an elevation of the complete tool.

Figure 2 is an enlarged section on line 2-2, Figure 1.

Figure 3 is an enlarged section on line 3-3, Figure 1.

Figure 4 is an enlarged plan view of the butt end of the blade.

Figure 5 is an enlarged plan view of the blade engaging end of the handle, the reinforcing straps being removed.

The tool consists of a handle, preferably of wood, attached to a thin steel blade. The manner of attaching the handle to the blade and the arrangement and construction of the handle and blade where they are connected together present most important advantages over other tools intended to do the same work.

Referring to the figures it will be noted that the handle 1 has one end enlarged as at 2 and formed with substantially square edge portions 3 which are parallel. The enlarged end has flat faces 4 and its width is greater than its thickness. A slot 5, which is parallel with the wide flat faces, extends

into the enlarged end of the handle midway between said faces and terminates in a straight inner wall 6 extending transversely of the handle. The end of the handle is beveled toward the slot as shown at 7.

The blade 8 is formed of thin steel and its width is greater than the width of the faces 4. A hook 9 is preferably provided at one end of the blade while the other end has its corners cut away along oblique lines as at 10, leaving a straight transverse end 11 of the same length as the wall 6 and adapted to bear thereagainst.

The thickness of the blade is the same as the distance between the opposed walls of slot 5 so that the blade will fit snugly in the slot and project in opposite directions from the handle.

Two pairs of openings 12 and 13 are formed in the handle near the ends of the slot and these openings are located between the center and side edges of the handle. They coincide with openings 14 and 15 formed in the blade and are adapted to register with openings 16 in transverse reinforcing straps 17 which extend across the flat faces 4 of the handle. Rivets 18 or the like extend through the openings 12, 13, 14, 15 and 16 and when upset serve to hold the handle clamped tightly on the blade. The ends of the straps 17 lap the sides of the handle as shown at 19 and extend close to the blade. These ends fit snugly against the sides of the handle and serve to relieve the handle from splitting strains as will be obvious.

It will be seen that as the rivets extend through the steel blade and through the handle and are arranged in rows of two each, these rows being located near the edges of the flattened portion of the handle, the wood material composing the handle extends between the rows of rivets and there is no splitting strain experienced whatever by this arrangement. Further as the outside edges of the handle are fully protected by the straps clamped securely down over them the handle is not subjected to unprotected strain. As the handle is located at equal distances from each edge of the blade it thereby allows a sufficient portion of the blade to be exposed so

as to permit sharpening and use as a cutting edge and as the handle is fully protected on both sides and both edges alike, the blade may be sharpened on one edge, or both edges, as desired and may be used for cutting with either edge or both edges.

What is claimed is:

A tool of the class described including a handle having an angular end portion with 10 flat faces, there being a slot extending into said end portion parallel with and equi-distant from opposed faces of said end portion, a thin cutting blade having a butt end fitted snugly into the slot and against the end wall

15

thereof, said blade having its edges disposed out of line with the handle, opposed straps snugly embracing the slotted angular portion of the handle and extending close to the blade, and spaced pairs of tie devices extending through the straps, handle and blade at points between the longitudinal center and the sides of the slot, thereby to provide a relatively broad imperforate middle portion of the handle extending longitudinally between 75 said devices.

In testimony that I claim the foregoing as my own, I have hereto affixed my signature.

LORENZO DOW PENDER.
